8 Claims. (Cl. 260—397.7)

1

This invention relates to processes for the manufacture of N¹-acylated amino aryl sulphonamides.

Among the large number of derivatives prepared from sulphanilamide, compounds of the formula

which are acylated at the N¹-position have, among others, proved in particular to be of excellent pharmacological effect. These also have the valuable property of forming in water easily soluble, almost neutral alkali salts eminently suitable for injection purposes.

In addition to medical purposes, compounds of this type are of interest also in the field of plasticizers, as a dyestuff component, and as a starting material for disinfectants and insecticides, etc.

The preparation of amino sulphonamides acylated at the N¹-position is the subject of numerous publications and patents. The most obvious way to mono-acylate the N¹-amino group of amino-aryl-sulphonamides, when following the usual instructions, having failed by previous experience (see, e. g., U. S. Patent No. 2,454,104, page 1, line 5), it has been attempted first to proceed by way of the N¹,N⁴-diacyl compound and subsequently selectively to split off the acyl group attached at the N⁴-position. Processes of this kind have the disadvantage that they must be carried out in two stages of manufacture.

Previously a mono-acylation at the N¹-nitrogen atom has been possible only in organic solvents in the presence of strong mineral acids (see U. S. Patent No. 2,454,104 of November 16, 1948, U. S. Schering Co.; and Swiss Patent No. 260,993, Class 116h, of November 1, 1949, Dr. A. Wander A. G., Bern), and it is necessary to take strict care to exclude water. As a matter of course, heavy corrosion is to be expected with this method of working.

In acylating amino-aryl sulphonamides with a free amino group in an alkaline aqueous medium, by previous experience, an acylation has been possible only at the N⁴-position or at both the N¹- and N⁴-positions. In accordance with that method, it has not been possible to prepare in a single stage products that are preponderantly acylated at the N¹-position where the formation of diacyl compounds as intermediate products is to be avoided (see, e. g., Norwegian Patent No. 63,307 (Schering), Example 8, and Chem. Berichte 83, 553 (1950)). See also British Patent No. 642,013

2

of August 23, 1950, in which also the indirect way, over diacyl products or the nitro compound, is described, which intermediate products must be performed subsequently into compounds with a free amino group, by saponification or reduction; thus a multi-stage process appears also necessary here.

Surprisingly it has been found that in amino-aryl sulphonamides with a free amino group also the desired N¹-acyl compound may be obtained in a single operation with satisfactory yields by a treatment of amino-aryl sulphonamides with acylating agents, if the reaction is conducted so that the reaction mixture remains alkaline during the entire reaction. For this purpose it is suitable to use such an amount of free alkali that a pH of approximately 9 to 14, preferably 11 to 14, prevails from the beginning to the end of the acylation.

Carboxylic acid anhydrides or halides, especially chlorides, e. g., of acetic acid, propionic acid, butyric acid, β - β -dimethylacrylic acid, benzoic acid, may be used as acylating agents.

Suitably the reaction proceeds with a moderate increase of temperature and in this case it will be completed within a short time.

The separation of the desired N¹-acyl product from a moderate amount of unreacted starting product may be effected easily by precipitation with a pH changed step by step, in the manner known.

It may be mentioned here that the amino aryl sulphonamides to be taken into consideration may consist, instead of sulphanilamide or the corresponding o- and m-products used as starting material, as mentioned in the examples, of derivatives of the same that are substituted at the aryl nucleus with alkyl-, halogen-, nitro-, acylamino groups, etc.

As compared with the previously known methods the new method of working provides the advantage of being carried out in a non-corroding medium and of the reaction being completed in a single-stage operation and within short time, whereas only that amount of acylating agent is used which is just required for an acyl group to be introduced.

Example 1.—0.1 mol=17.2 g. of sulphanilamide, 0.3 mol=12 g. of caustic soda, and 20 c. c. of water are brought into solution by being heated (approximately 75° C.). At this temperature while the solution is being stirred 0.154 mol=14.5 c. c. of acetic anhydride are added in drops, in the course of 15 minutes. After being stirred for further 15 minutes the solution is diluted with some water, to obtain in solution the sodium

salts separating in the cold, and is adjusted to pH 8 with some hydrochloric acid. After separating unreacted sulphanilamide (6.9 g.) a further acidulation to pH 4 leads to the precipitation of 10.7 g. of crude N¹-acetyl compound, 5 which yields 9.6 g. of pure N¹-acetyl sulphanilamide after a single recrystallization from a small amount of water (melting point 180° to 181° C.).

Taking into account the starting material recovered the yield of pure N¹-acetyl sulphonamide is more than 70% of theory, and where the starting material recovered is not taken into account the yield is 45% of theory.

Example 2.—1 mol=172 g. of sulphanilamide, 15 1.125 mol=45 g. of caustic soda, and 200 c. c. of water are brought into solution (approximately 45° C.) and at this temperature, while the solution is being stirred, a solution of 1.925 mol=77 g. of caustic soda in 100 c. c. of water, on the 20 one hand, and 1.44 mol=136 c. c. of acetic anhydride, on the other hand, are separately though at the same time added thereto within 30 minutes.

After being stirred for further 15 minutes the 25 solution is diluted with some water and is adjusted with concentrated hydrochloric acid to pH 8. After the separation of unreacted sulphanilamide (30.3 g.) a further acidulation to pH 4 leads to the precipitation of 130 g. (approximately 60% of theory) of crude N¹-acetyl compound, which after recrystallization from water 30 yields 116 g. of pure N¹-acetyl sulphanilamide (54% yield); when the starting material recovered is taken into account this yield of pure N¹-acetyl product (melting point 180° to 181° C.) is 35 increased to 66%.

In the same manner, when starting from sulphanilamide, N¹-β,β-dimethylacrylic sulphanilamide (M. P. 177°-178° C.) may be obtained with β,β-dimethylacrylic acid anhydride, N¹-propionic sulphanilamide (M. P. 134°-135° C.) with propionic anhydride, N¹-butyric sulphanilamide (M. P. 125°-126° C.) with butyric anhydride, and N¹-benzoic sulphanilamide (M. P. 181°-182° C.) with benzoic chloride.

I claim:

1. A process for making N¹-acylated 4-aminoaryl sulphonamides which have a free primary amino group attached directly to the aryl radical, 50 comprising the steps of dissolving 4-aminoaryl sulphonamide in an alkaline medium, reacting said dissolved 4-aminoaryl sulphonamide in a single stage with an anhydride of a monocarboxylic acid, while maintaining the pH of the reaction mixture between 9 and 14 during the entire reaction, and separating the reaction product therefrom.

2. The process as claimed in claim 1, wherein the pH of the reaction mixture is maintained between 11 and 12.

3. A process for making N¹-acylated 4-aminoaryl sulphonamides which have a free primary amino group attached directly to the aryl radical, comprising the steps of dissolving 4-aminoaryl sulphonamide in an alkaline medium, reacting said dissolved 4-aminoaryl sulphonamide in a single stage with an anhydride of a monocarboxylic acid selected from the group consisting of acetic acid, propionic acid, butyric acid, β,β-dimethyl acrylic acid and benzoic acid, while maintaining the pH of the reaction mixture between 9 and 14 during the entire reaction, and separating the reaction product therefrom.

4. A process as claimed in claim 3, wherein the pH of the reaction mixture is maintained between 11 and 12.

5. A process as claimed in claim 3, wherein the said alkaline medium is a solution of sodium hydroxide in water.

6. A process as claimed in claim 5, wherein the pH of the reaction mixture is maintained between 11 and 12.

7. A process for making N¹-acylated 4-aminoaryl sulphonamides having a free primary amino group attached directly to the aryl radical, comprising the steps of dissolving 4-aminoaryl sulphonamide in a solution of sodium hydroxide in water, reacting said dissolved 4-aminoaryl sulphonamide with an anhydride of a monocarboxylic acid selected from the group consisting of acetic acid, propionic acid, butyric acid, β,β-dimethyl acrylic acid and benzoic acid, at elevated temperatures between 30° C. and 75° C., while maintaining the pH of the reaction mixture between 9 and 14 during the entire reaction, and separating the reaction product therefrom.

8. A process as claimed in claim 7, wherein the pH of the reaction mixture is maintained between 11 and 12.

JOSEF MATZKE.
